UNITED STATES PATENT OFFICE

GLENWAY M. RIX, OF CEDARBURG, WISCONSIN, ASSIGNOR TO SQUIER-RIX COMPANY,
OF MILWAUKEE, WISCONSIN

HOISTING DEVICE

Application filed January 5, 1925. Serial No. 635.

This invention relates to improvements in hoisting devices, more particularly adapted for use with tractors of the "Fordson" type and others.

5 It is one of the objects of the present invention to provide a hoisting device which may be easily mounted upon a tractor and which will conveniently handle any load within its capacity in a very simple manner.

10 A further object of the invention is to provide a hoisting device which may be used for hoisting, or when slightly modified can be used for excavating purposes.

15 A further object of the invention is to provide a hoisting device in which the hoisting mechanism will automatically support its load while at rest.

20 A further object of the invention is to provide a hoisting device which is connectible to and is driven by the power means of the tractor.

25 A further object of the invention is to provide a hoisting device which is of simple construction, is strong and durable, and is well adapted for the purpose described.

With the above and other objects in view, the invention consists of the improved hoisting device and its parts and combinations as set forth in the claims, and all equivalents 30 thereof.

In the accompanying drawings, in which the same reference characters indicate the same parts in all of the views:

Fig. 1 is a side view of the improved hoisting device shown mounted on a tractor;

Fig. 2 is a vertical sectional detail view taken on line 2—2 of Fig. 1;

Fig. 3 is a sectional detail view taken on line 3—3 of Fig. 2;

Fig. 4 is a sectional detail view on a larger scale, taken on line 4—4 of Fig. 2.

Fig. 5 is a side view of a modified form of device adapted for use as an excavator or digger; and

Fig. 6 is a detail view on a larger scale, of the driving mechanism shown in Fig. 5.

Referring to the drawings, the numeral 8 indicates a tractor of the "Fordson" type which is provided with the usual power take off shaft 9. The improved hoisting device

is mounted on the tractor and comprises a frame 10 consisting of vertical members 11, upper angular members 12 having extension boom portions 13 and brace members 14. The lower ends of the angular members 12 are 55 provided with brackets 15 which surround the bearings of the rear wheels of the tractor, while the front vertical members 11 are connected to the frame 8' of the tractor. A shaft 16 journaled on the upper portion of the frame is provided with a drum 17 upon which a lifting cable 18 is wound. Said cable extends forwardly over a grooved wheel 19 mounted on the outer end portion of the boom, and at its lower end is provided with 60 a hook 20 for convenience in connecting to the loads to be moved. The drum is journaled on the shaft and is provided with a hook 21 which are engaged by the teeth of a clutch collar 22 slidably but non-rotatably mounted on said shaft. A shift lever 23 controls the movement of said clutch collar to permit the drum to turn freely on the shaft in unwinding the cable therefrom. A counter shaft 24 mounted below the shaft 16 is 65 provided with a gear wheel 25 which meshes with a gear wheel 26 mounted on the shaft 16. The outer end of the shaft 24 is provided with a worm wheel 27 in mesh with a worm 28 mounted on a short second counter shaft 29 70 extending at right angles to the shaft 24. A counter shaft 24 mounted below the shaft 16 is 75 provided with a gear wheel 25 which meshes with a gear wheel 26 mounted on the shaft 16. The outer end of the shaft 24 is provided with a worm wheel 27 in mesh with a worm 28 mounted on a short second counter shaft 29 80 extending at right angles to the shaft 24. One end of said short shaft is provided with a bevel gear 30, and a short third counter shaft 31 extending transversely of the end of the shaft 29 is provided with two bevel gears 85 32 which are in constant mesh with opposite sides of the bevel gear 30. The bevel gears 32 are journaled on the shaft 31 and are each provided with clutch faces 33 which are 90 adapted to be engaged by a clutch collar 34 splined on the shaft 31 to reverse the direction of rotation of the drum 17. A clutch lever 35 controls the clutch collar 34. The outer ends of the shafts 9 and 31 have sprocket 95 wheels 36 and 37 mounted thereon which are engaged by a sprocket chain 44 to transmit power from the tractor shaft 9 to the reversing shaft 31 for operating the hoisting mechanism. As thus constructed, the power of the tractor will be increased by means of the 100

worm and worm wheel and gear transmission, and the worm and worm wheel being non-reversible, will automatically hold the load in suspended position.

5 In the modified form shown in Figs. 5 and 6, the frame is slightly modified by providing a longer brace member 14 and mounting a pulley and shaft 19' medially thereon which is connected to rotate a gear 38 which is in mesh with a rack bar 39 slidably positioned in front of the tractor. A scoop shovel 40 having a hinged bottom portion 41 is carried by the lower end of the rack bar 39 and is adapted to be raised or lowered by the gear 38. A shaft 42 journaled on the upper portion of the frame 12 has a geared connection 43 with the drum shaft 16 and is driven thereby. A sprocket chain and wheel connection 44' is provided between the shafts 42 and 19' to transmit motion thereto. The cable 18 instead of being connected to the hook 20 passes around a pulley 45 mounted on the scoop and then extends upwardly to the outer end of the extension boom and is connected thereto, as indicated by the numeral 46, to provide a forward scooping movement of the scoop and also to lift the scoop and its load. A locking pin 47 controlled by a cable 48 is provided for unlocking the bottom portion of the scoop 30 shovel to discharge the load thereof. The transmission gearing is enclosed in a suitable casing 49 to protect the same and act as a guard against accidental injury to the operator.

35 From the foregoing description, it will be seen that the hoisting device is of very simple construction, is easy to operate, will automatically hold the load in suspended position, and is well adapted for the purpose described.

40 What I claim is:

1. The combination with a tractor having a driving shaft, of a hoisting device therefor, comprising a frame mounted on the tractor and having an extension forming a boom, a shaft journaled on the frame, a drum journaled on the shaft, a clutch means for connecting the drum to the shaft, a counter shaft journaled on the frame and having a geared connection with the drum shaft, a second counter shaft journaled on the frame and having a non-reversible worm and worm-wheel connection with the first counter shaft, a third counter shaft journaled on the frame, gears journaled on the third counter shaft and having a geared connection with the second counter shaft, clutch means for positively connecting either one of the last mentioned gears to the third shaft, means for drivingly connecting the third counter shaft to the driving shaft, and a cable connected to the drum and extending towards the boom.

2. The combination with a tractor having a rear axle and driving shaft of a hoisting device therefor, comprising oblique frame

members mounted on the tractor and extending upwardly from the rear axle and forwardly therefrom to form a boom, a shaft journaled on the upper portion of the frame members, a drum journaled on the shaft, a clutch means for connecting the drum to the shaft, a counter shaft journaled on the frame and having a geared connection with the drum shaft, a second counter shaft journaled on the frame and having a non-reversible worm and worm wheel connection with the first counter shaft, a third counter shaft journaled on the frame, gears journaled on the third counter shaft and having a geared connection with the second counter shaft, clutch means for positively connecting either one of the last mentioned gears to the third shaft, a sprocket wheel and sprocket chain driving connection between the third counter shaft and the driving shaft, and a cable connected to the drum and extending towards the boom.

3. The combination with a tractor having a driving shaft, of a hoisting device therefor, comprising angular upper frame members mounted on the tractor and having extensions forming a boom, a pulley journaled on the boom, vertical members mounted on the tractor and connected to the upper members, brace members connected to the said members, a shaft journaled on the upper frame members, a drum journaled on the shaft, a clutch means for positively connecting the drum to the shaft, a counter shaft journaled on the frame and having a geared connection with the drum shaft, a second counter shaft journaled on the frame and having a non-reversible worm and wormwheel connection with the first counter shaft, a third counter shaft journaled on the frame and having a pair of bevel gears journaled thereon which are in mesh with a bevel gear mounted fast on the second counter shaft, clutch means for locking either one of the pair of bevel gears to the third shaft, a sprocket wheel and sprocket chain driving connection between the third counter shaft and the driving shaft, one of the sprocket wheels being journaled on the shaft, a clutch means for locking the journaled sprocket wheel to its shaft, and a cable mounted on the drum and extending over the pulley for connection with a work instrumentality.

4. The combination with a tractor having a driving shaft, of a hoisting device therefor, comprising a frame mounted on the tractor and having an extension forming an upwardly extending boom, a shaft journaled on the frame, a drum journaled on the shaft, a clutch means for connecting the drum to the shaft, a counter shaft journaled on the frame and having a geared connection with the drum shaft, a second counter shaft journaled on the frame and having a worm and worm wheel connection with the first counter shaft, a third counter shaft journaled on the frame, gears journaled on the third counter shaft

and having a geared connection with the second counter shaft, clutch means for positively connecting either one of the last mentioned gears to the third shaft, a sprocket wheel and sprocket chain driving connection between the third counter shaft and the driving shaft, and a cable connected to the drum and extending towards the boom.

5 In testimony whereof, I affix my signature.
GLENWAY M. RIX.
